MOUNTING OF MOTORS

Russell T. Smith, Greenville, Mich., assignor to
 Gibson Refrigerator Company, Greenville,
 Mich., a corporation of Michigan

Application June 26, 1931, Serial No. 547,161

9 Claims. (Cl. 62—116)

This invention relates to electric refrigerators and more especially to such refrigerators particularly adapted for household and domestic use.

An object of this invention is a removable refrigerator unit including a mounting board which serves as an insulating closure for the open top of the refrigerator food storage compartment as a support for a depending evaporator, and as a support for a motor, a compressor, a condenser, and a float valve, these last all being enclosed within a buffet top cover or hood.

A construction of this character is particularly adapted for domestic use since it is mounted in the cabinet as a unit, and in the event of repairs, can be removed from the cabinet as a unit and replaced by a similar unit, thus eliminating the necessity of disassembly or repairs at points other than the factory or authorized service stations.

Further, the unit of the invention is simple, neat of appearance, economical and facile of manufacture, and lighter in weight than constructions heretofore provided for this purpose.

Still further objects will readily occur to those skilled in the art upon reference to the following description and the accompanying drawings in which

Fig. 1 is a partial transverse section thru the top of a refrigerator, with the unit in place.

Fig. 2 is a top plan view of a portion of a refrigerator, with the unit in place, and the buffet top or cover being removed.

Fig. 3 is an end section as if on the line 3—3 of Fig. 2, with the cover in place.

Referring to the drawings it will be seen that the refrigerator includes a wall having an outer metallic shell 10, an inner metallic shell 12, and an insulating filler 14, of well known construction. The outer wall is continued for quite some distance above the inner wall and the insulation, and is provided with a buffet top or cover 16, there being thus formed an enclosed compartment above the top of the refrigerator proper. The open top of the food storage compartment inside the wall 12 is closed by the unit closure of the invention and the construction of the same will now be described.

The unit closure, in part, comprises a horizontal support 20, which includes two sheet metal plates 22 and 24 insulated from each other by the filler of insulating material indicated. The lower plate has a peripheral retaining flange 25 and rests upon a gasket 26 and upon the out-turned edge 28 of the wall 12. The upper plate also has a flange 29, and rests on a gasket 30

disposed upon the sheet metal plate 32 which covers insulation 14.

The horizontal support also includes wooden blocks, two of which are shown at 36, these serving to support the evaporator, and to secure all of the parts of the horizontal support together. Being of wood, they prevent heat transfer between plates 20 and 22. These wooden blocks are secured to the upper plate 22 by screws 38 and have vertical bores 39 passing therethru and terminating in counterbores 40 beneath the plate 42, the bores being spaced from or staggered with respect to the screws 38, as can be readily seen from Fig. 2.

Passing thru the bores 39 and having their heads 42 resting upon the lower surface of the counterbores 40, are screw bolts 44 which serve as supports for the depending evaporator 46, the latter having its boiler 48 provided with brackets 50 thru which pass the lower ends of the bolts 20 44, there being nuts 52 threaded onto these bolts to secure the evaporator in place.

The upper plate 22 of the horizontal insulating support is provided with a plurality of (four) depressions 56 in which are loosely disposed resilient mounting blocks or spheres 58. These balls, which are preferably of rubber, are received in raised portions 60 of the parallel rails 62 to which the motor-compressor 64 is secured, the balls thus serving as resilient floating supports 30 for the motor-compressor unit.

A float valve 68 also rests on the plate 22 and is connected to the condenser 70 which also rests upon the plate 22, all of these parts and their connections being within the peripheral flange 35 29 of the upper plate 22.

In order to hold down the motor against vibration suitable means are provided and one form of such means is illustrated. In this form, stirrups 76 are secured to the plate 22, outside of the rails 62. Transverse bars or straps 78 resting on and straddling the rails 62 have their ends disposed in the stirrups 76 and pressure is brought on these bars by screws 80 which thread thru the stirrups and against the ends of the bars 78 45 to bear down upon the latter and consequently upon the rails to which is secured the motor.

For convenience in lifting the unit out of the refrigerator when the top 16 is removed, bail-like handles 82 are secured to the peripheral flange 29 at the ends of the latter, as can be seen on the drawings.

From the foregoing, it will be observed that there has been provided a unit closure construction for the open top of a refrigerator cabinet.

the construction being in the nature of a one piece or unit closure and mounting which has all the advantages previously set forth.

Now having described the invention and the preferred embodiment thereof, it is to be understood that the said invention is to be limited, not to the specific details herein set forth, but only by the scope of the claims which follow:—

What I claim is:—

- 10 1. In a refrigerator having an open top cabinet, a unit closure for the open top comprising a horizontal insulating support, an evaporator under, secured to, and supported by said support, and a refrigerator power plant floatingly resting on said support, the support including two spaced sheet metal plates, separated by wooden blocks, means fastening the blocks to the uppermost plate, and means passing thru the block for supporting the evaporator.
- 15 2. In a refrigerator having an open top cabinet, a unit closure for the open top comprising a horizontal insulating support, an evaporator under, secured to, and supported by said support, and a refrigerator power plant floatingly resting on said support, the support including two spaced sheet metal plates, separated by wooden blocks, means fastening the blocks to the uppermost plate, and means passing thru the block for supporting the evaporator, the parts being so disposed that no metallic part is in contact with both of said plates.
- 20 3. In a refrigerator having an open top cabinet, a unit closure for the open top comprising a horizontal insulating support, an evaporator under, secured to, and supported by said support, and a refrigerator power plant floatingly resting on said support, the support including two spaced horizontal sheet metal plates separated by wooden blocks and other insulating material, means fastening the blocks to the uppermost plate, and means spaced from the first mentioned means and passing thru said blocks out of contact with the upper plate for supporting the lower plate and the evaporator.
- 25 4. In a refrigerator having an open top cabinet, a unit closure for the open top comprising a horizontal insulating support, an evaporator under, secured to, and supported by said support, and a refrigerator power plant floatingly resting on said support, the support including two spaced sheet metal plates, separated by wooden blocks, means fastening the blocks to the uppermost plate, and means passing thru the block for supporting the evaporator, the upper plate having depressions in which are disposed rubber mounting balls upon which the power plant rests, the latter having rails secured to and beneath the power plant proper and provided with raised portions in alignment with the plate depressions, the balls being in the raised portions as well as in the depressions, and means secured to the upper plate contacting with said rails for holding down the latter and the power plant.
- 30 5. In a refrigerator having an open top cabinet, a unit closure for the open top comprising a horizontal insulating support, an evaporator under, secured to, and supported by said support, and a refrigerator power plant floatingly resting on said support, the support including two spaced sheet metal plates, separated by wooden blocks, means fastening the blocks to the uppermost plate, and means passing thru the block for supporting the evaporator, the upper plate having depressions in which are disposed rubber mounting balls upon which the power plant rests.
- 35 6. In a refrigerator having an open top cabinet, a unit closure for the open top comprising a horizontal insulating support, an evaporator under, secured to, and supported by said support, and a refrigerator power plant floatingly resting on said support, the support including two spaced sheet metal plates, separated by wooden blocks, means fastening the blocks to the uppermost plate, and means passing thru the block for supporting the evaporator, the support having upwardly extending bail-like handles secured thereto by means of which the unit closure as a whole may be lifted from the cabinet.
- 40 7. In a refrigerator having an open top cabinet, a unit closure for the open top comprising a horizontal insulating support, an evaporator under, secured to, and supported by said support, and a refrigerator power plant floatingly resting on said support, the support including two spaced sheet metal plates, separated by wooden blocks, means fastening the blocks to the uppermost plate, and means passing thru the block for supporting the evaporator, the upper plate having depressions in which are disposed rubber mounting balls upon which the power plant rests, the latter having rails secured to and beneath the power plant proper and provided with raised portions in alignment with the plate depressions, the balls being in the raised portions as well as in the depressions, and means secured to the upper plate contacting with said rails for holding down the latter and the power plant.
- 45 8. In a refrigerator having an open top cabinet, a unit closure for the open top comprising a horizontal insulating support, an evaporator under, secured to, and supported by said support, and a refrigerator power plant floatingly resting on said support, the support including two spaced sheet metal plates, separated by wooden blocks, means fastening the blocks to the uppermost plate, and means passing thru the block for supporting the evaporator, the upper plate having depressions in which are disposed rubber mounting balls upon which the power plant rests, the latter having rails secured to and beneath the power plant proper and provided with raised portions in alignment with the plate depressions, the balls being in the raised portions as well as in the depressions, and means secured to the upper plate contacting with said rails for holding down the latter and the power plant, the means including spaced stirrups connected to the upper plate, bars having their ends loosely disposed in the stirrups and crossing the rails, and screws in said stirrups for moving said bars and rails vertically.
- 50 9. In an electric refrigerator including a compressor, means for mounting said compressor comprising a bed plate to which said compressor is fixed, a second plate fixed to the refrigerator structure and underlying said bed plate, said plates each having a plurality of depressions, the depressions in each plate opening toward the other plate and each depression opposed to a depression in the other plate, and a loosely disposed rubber ball in each pair of depressions of sufficient diameter to maintain said plates in spaced relation, and means to limit relative lateral displacement of said plates, said limiting means including stirrups on one of said plates and bars fixed in said stirrups and overlying portions of the other of said plates.
- 55 10. In a refrigerator having an open top cabinet, a unit closure for the open top comprising a horizontal insulating support, an evaporator under, secured to, and supported by said support, and a refrigerator power plant floatingly resting on said support, the support including two spaced sheet metal plates, separated by wooden blocks, means fastening the blocks to the uppermost plate, and means passing thru the block for supporting the evaporator, the upper plate having depressions in which are disposed rubber mounting balls upon which the power plant rests, the latter having rails secured to and beneath the power plant proper and provided with raised portions in alignment with the plate depressions, the balls being in the raised portions as well as in the depressions.
